UNITED STATES PATENT OFFICE.

FRANK ROEHR, OF CHICAGO, ILLINOIS.

GUARD-GATE FOR SWING-BRIDGES.

SPECIFICATION forming part of Letters Patent No. 255,026, dated March 14, 1882.

Application filed October 13, 1881. (No model.)

To all whom it may concern:

Be it known that I, FRANK ROEHR, of Chicago, in the county of Cook and State of Illinois, have invented certain new and useful Improvements in Guard-Gates for Swing-Bridges; and I do hereby declare the following to be a full, clear, and exact description of the invention, that will enable others skilled in the art to which it appertains to construct and operate the same, reference being had to the accompanying drawings, and to letters of reference marked thereon, forming a part of this specification.

This invention is an improvement on Letters Patent No. 225,535 of March 16, 1880.

This invention relates to an improvement in safety or guard gates to be placed on the approaches of draw or pivot bridges for the purpose of closing the passage-ways and guarding against accidents during the time that the draw is open. The operating mechanism is so constructed and arranged that the gates are automatically opened and closed by the movement of the bridge and operates with equal facility whether the bridge is swung in one direction or the other.

Figure 1 is a transverse section, looking from the central pier supporting the bridge. Fig. 2 shows the position of the guard-gates when closing the passage-ways, the bridge being swung; Fig. 3, a vertical longitudinal section, and Fig. 4 a detached view of the angular levers operating the side gates.

Referring to the drawings, A represents the vertical posts, and A' the connecting cross-beam, which forms the main supporting framework for the gates.

A² is the bridge-approach upon which the supporting frame-work is placed; A³, the bridge proper; B, the main central gate, and a the side gates or bars.

The hollow uprights or posts A are ordinarily constructed of heavy planking, and may be set on the bridge-approach at any convenient point, either close up to the edge or farther back on the approach. The main central gate, B, for closing the driveway has a vertical movement between the posts A, and is operated by means of the cords or chains D. One end of these cords is attached to the upper corners of the main gate, as shown by the dot-

ted lines in Fig. 1 of the drawings, and passes upward and over the sheaves D', and from thence downward through the interior of the posts A, and under the sheaves D² to the drum 55 or pulley C, the lower end of one cord passing under and the other over the drum C, as shown in Fig. 1 of the drawings. This arrangement throws an equal strain on each end of the gate, as the rotation of the drum C winds 60 up or unwinds both cords at the same time. The principal portion of the operating mechanism is located beneath the bridge-approach, as shown in the several figures of the drawings. The drum C is rotated on the shaft B', upon 65 the outer end of which is placed the pinion d, which is adapted to engage with the gear-wheel d', located upon the shaft d². On the outer end of the shaft d² is placed the rocker-arm C', upon the upper end of which is the 70 friction-roller C², which has a frictional contact with the beveled cleat C³, attached to the under side and near the immediate end of the bridge, as shown in Fig. 1 of the drawings. When the bridge is closed and the passage-way open the lever or rocker-arm C' will either 75 incline to the right or left of a vertical line, in accordance with the direction in which the bridge has been closed. When the bridge is being opened the lever-arm C will gradually 80 assume a vertical position, and the main gate slowly descends by the force of gravity, and when the main gate is down and the lever-arm released from contact with the under side of the bridge the lever-arm rests in a vertical 85 plane, as shown in Fig. 2 of the drawings.

The operation is very simple. As the bridge moves in one direction the drum C is rotated through the medium of the pinion d, the gear-wheel d', and the lever-arm C by reason of its 90 bearing on the under side of the bridge. When the bridge is moved the drum C rotates, and the cords attached to the main gate are wound up or unwound as the gate ascends or descends with the opening or closing of the bridge. The 95 lower ends of the cords or chains D are usually secured to the exterior surface of the drum C by means of ordinary staples; or the ends of the cords may pass through the shell of the drum and be secured on the inside thereof in 100 any suitable manner. The side gates or bars, a, for closing the foot passage way are recessed

into the parts A, and are pivoted thereto, as shown in Fig. 2 of the drawings. The inner ends of the bars a have the semicircular or enlarged part a³, the upper side being grooved 5 out for the reception of the operating-cord a', the upper end of this cord being attached to the bar a, and then running down and passing under the sheave a⁴, and attached to the eye or lower end, b, of the angular lever a², a detached view of which is given in Fig. 4 of the 10 drawings. This angular lever has an operating-bearing in the staple or eye b', the upper end having a frictional contact with the under side of a downward-projecting part of the cleat 15 C³. When the bridge is closed the bars or side gates are raised to a vertical position in the posts A and the angular lever a² assumes the position shown in Fig. 2 of the drawings. The

spring b², placed in the recess and at the back side of the side gates, a, serves the purpose of 20 starting the side gates toward a horizontal position, and insuring a positive action at all times.

Having thus described my invention, what I claim, and desire to secure by Letters Patent, is—

25 The combination, with the drum C, the shaft B', the pinion d, the gear-wheel d', the gear-wheel shaft d², the lever-arm C', the friction-roller C², the beveled cleat C³, and the bridge A³, all constructed, arranged, and operating as 30 herein shown and described.

FRANK ROEHR.
